Ryan K. Simmons

(57) **CLAIM**

The ornamental design for a closeable container, as shown and described.

DESCRIPTION

FIG. 1 is a perspective view of a closeable container showing a new design;

FIG. 2 is a right side elevation view thereof, the left side being a mirror image;

FIG. 3 is a front elevation view thereof;

FIG. 4 is a rear elevation view thereof;

FIG. 5 is a top plan view thereof;

FIG. 6 is a bottom plan view thereof; and,

FIG. 7 is another perspective view thereof, showing the closeable container in an open configuration.

In FIGS. 1, 2, and 7 the dotted lines are for the purpose of illustrating perforations. In FIGS. 1, 5, and 7 the dash-dash broken lines are for the purpose of illustrating environment only and form no part of the claimed design.

1 Claim, 7 Drawing Sheets
